UNITED STATES PATENT OFFICE

98,267

DESIGN FOR A SHOW CASE OR SIMILAR ARTICLE

Richard H. Marr, Detroit, Mich., assignor to Detroit Show Case Company, Detroit, Mich., a corporation of Michigan

Application May 27, 1935, Serial No. 57,032

Term of patent 7 years

To all whom it may concern:

Be it known that I, Richard H. Marr, a citizen of the United States, residing at Detroit, in the county of Wayne and State of Michigan, have invented a new, original, and ornamental Design for a Show Case or Similar Article, of which the following is a specification, reference being had to the accompanying drawing, forming part thereof.

The figure is a perspective view of a show case or similar article showing my new design.

I claim:

The ornamental design for a show case or similar article, as shown.

RICHARD H. MARR.
